Coheneyen Dwyer
Salem Patent

6119X

The schedule referred to in these Letters Patent and making part of the same containing a description in the words of the said Coheneyen Dwyer himself of his improvement in the Chemin called the "Float Wheel Chemin."

Said Chemin consists of a concrete cylinder or barrel which opens horizontally thro' the centre lengthwise and is thereby divided into two equal parts which I denominate the upper & lower part of the Chemin. To prevent the mith & earth escaping from the Chemin when it is in operation the upper part is inserted or let into the lower part by a lip or projection (from the inner side of the lower edge of the said upper part) which exactly fits & fills a cabbetting upon the inner side of the upper edge of said lower part which cabbetting & projection are an inch or more wide so that when the Chemin is shut the joint between the upper & lower part is covered by the said projection & is rendered nearly tight. To the ends of the lower part of the Chemin are attached 4 legs 2 upon each end 2 feet long which raise the Chemin a suitable height from the floor for convenience. On the sides of the Chemin 2 upon each part are 4 handles with which to move the Chemin. On the lower side of one end of the Chemin is an inole hole with a plug in top to it there is with the latter mith & earth is let out of the same & on the top of the upper part is a small hole to permit the air to escape from the Chemin when it is in motion.

The size of a common Chemin is 18 inches in diameter & 12 inches in length on the outside but these dimensions may be varied at pleasure. The float wheel by which the operation of Chemining is effected consists of an axis or shaft which passes thro' the centre of the cylinder at right angles to its diameter. The outer end of the shaft is fastened to its place in the centre by being inserted into a bearing on the centre of the inside of one end of the cylinder. The other end of the shaft to which the wheel is attached projects from the cylinder 2 or 3 inches & is upon a bearing in the other end of the cylinder, the hub of which bearing is in the

204.

up & the other half on the lower part of the cylinder. On the end of the handle next to the crank & this wheel the st. 1/4 prop is placed a conductor which leads into the lower part of the cylinder. Said conductor is placed under the outer end of the shaft & conveys back into the chain the cream or milk which is put into between the shaft & oil bearing on that end of the chain. Said conductor is made by nailing it following in any other way a piece of board 3 or 4 inches wide & 6 long of ground or fasted on one side for 3 inches in length & 2 in width at the top & terminating in a point at 4 inches from the top where a hole is cut thro' into the chain & permits whatever comes from the cylinder to pass back into the chain. Into the cup which is 4 square are inserted 4 rows of floats or paddles each row being directly opposite to another row, each row consists of 3, 4, or more or less floats 2 inches wide & half an inch thick in the middle & an eighth of an inch thick at the edges & stand at right angles to the shaft lengthwise of the floats and in an angle of 45 degrees with the center of them so that when the floats lie horizontally the upper edge of each is elevated above the lower edge in an angle of 45 degrees with the surface of the cream & when the wheel is in operation the floats do not strike square against the cream but partly upright and partly sideways requiring but little power to operate it & each row of floats stands diagonally with the axis in a manner contrary or different from the row next to it each successive row of floats moves the cream in a direction contrary or opposite to the last preceding row & every revolution of the wheel gives the cream 4 motions besides dividing the cream as many times as there are floats in the wheel which keeps the cream with continual agitation with the application of very little power. The chain is opened (or cream put into it) that again with the wheel on it places the operation performed by means of the crank. The wheel is moved at pleasure & the chain cleaned with all imaginable care. The wheel may be made with more or less rows of floats & with more or less floats in a row & the different parts of the chain may be made in every respect. The method of agitating milk or cream with various other devices may be applied to all other cases. The crank or handle should be made 1 1/2 or 2 1/2 inches long according to the size of the chain. The cylinder

and that the above is a true specification of the improvement for which
such a Patent is also its use & application. These documents being hand
written this 24th day of August 1830.
